(57) **CLAIM**

The ornamental design for an electrocardiographic device, as shown and described.

DESCRIPTION

1. Electrocardiographic device

1.1 : is a top, front perspective view of an electrocardiographic device, showing my new design;

1.2 : is a front elevation view thereof;

1.3 : is a rear elevation view thereof;

1.4 : is a left side elevation view thereof;

1.5 : is a right side elevation view thereof;

1.6 : is a top plan view thereof;

1.7 : is a bottom plan view thereof; and,

1.8 : is a top, rear perspective view thereof.

In the drawings, the equal-length broken lines depict portions of the electrocardiographic device that form no part of the claimed design. The dash-dot-dash broken lines define the boundaries of the claimed design. All broken lines form no part of the claim.
